(73) Assignee: **Universal Surveillance Corporation**, Rancho Cucamonga, CA (US)

(57) **CLAIM**

(**) Term: **14 Years**

An ornamental design for an electronic article surveillance unit for use with articles, as shown and described.

(21) Appl. No.: **29/240,196**

DESCRIPTION

(22) Filed: **Oct. 11, 2005**

FIG. 1 is a right side perspective view of the electronic article surveillance unit for use with articles in an unengaged state showing the design;

(51) **LOC (9) Cl.** 10-05

FIG. 2 is a bottom side perspective view thereof in an unengaged state;

(52) **U.S. Cl.** D10/106

FIG. 3 is a rear side elevational view thereof in an unengaged state;

(58) **Field of Classification Search** D10/104,

FIG. 4 is a front side bottom perspective view thereof in an engaged state;

D10/106; D8/333; D3/208; 24/704.1; 340/10.1,
340/571, 572.1, 572.9, 572.8; 40/625; 292/307 A,
292/326; 224/221; 42/70.11; 70/16

FIG. 5 is a rearward bottom perspective view thereof in an engaged state;

See application file for complete search history.

FIG. 6 is a rearward top perspective view thereof in an engaged state;

(56) **References Cited**

FIG. 7 is a right side elevational view thereof in an engaged state wherein the left side is a mirror image of the same;

U.S. PATENT DOCUMENTS

FIG. 8 is a top plan view thereof in an engaged state; and,

FIG. 9 is a rearward plan view thereof in an engaged state.
